UNITED STATES PATENT OFFICE.

WILLIAM T. HENRY, OF LAKE CHARLES, LOUISIANA.

RECEPTACLE HOLDER.

Application filed March 19, 1926. Serial No. 95,925.

This improvement relates to new and useful improvements in a receptacle holder.

One object of the invention is to provide a device of the character described specially 5 designed for the purpose of holding soap trays, and similar containers and embodying a flexible vacuum cup for anchoring the holder to a suitable support.

Another object of the invention is to provide 10 a holder of the character described which may be readily detached from its support, when not in use.

A further feature of the invention resides 15 in the provision of a holder of the character described which is of simple and light construction and may be cheaply and easily produced and readily carried about for use.

With the above and other objects in view 20 the invention has particular relation to certain novel features of construction, arrangement of parts and use, an example of which is given in this specification and illustrated in the accompanying drawings, wherein:

Figure 1 shows a cross sectional view of 25 the soap tray, as mounted on a holder.

Figure 2 shows a bottom plan view of the tray and holder, and

Figure 3 shows a cross sectional view of 30 the tray showing a modified type of holder.

Referring now more particularly to the drawings wherein like numerals of reference 35 designate similar parts in each of the figures, the numeral 1 designates a container, a soap tray being illustrated in the present instance. The numeral 2 designates the holder as a whole, of the form shown in Figures 1 and 2. This type of holder is adapted to be secured to the top, as 3, of a wash basin, or other support in a horizontal plane. The 40 holder will preferably be formed of sheet metal, or other material and has the plate 4 forming an anchor for the vacuum cup 5. This cup is formed of rubber or other suitable flexible material and is applied to the surface 3 in the well known manner and is held thereon by the normal air pressure. The

plate 4 forms a platform on which the tray 1 rests and formed integrally with the plate there is the upturned bracket 6. This bracket is formed with a hook 7 which engages 50 over the adjacent edge of the tray. The bracket 6 has the integral outwardly turned legs 8, 8, whose free ends are turned into a common plane with the free edge of the vacuum cup 5 so as to rest on the surface 3 and 55 form braces for said tray.

In the form shown in Figure 3 the parts hereinbefore described are substantially similar to the corresponding parts shown in Figures 1 and 2 and are designated by similar 60 numerals, except that the vacuum cup 5 is anchored to the bracket 6 and is thereby adapted to be secured to the vertical side 9 of the basin or other support, as shown in Figure 3.

What I claim is:

1. A receptacle holder including a platform adapted to support a receptacle, a bracket integral with the platform and upstanding therefrom, spaced hooks carried by 70 said bracket adapted to engage the rim of the receptacle on said platform, a vacuum cup anchored to said holder and adapted to support the same and a leg forming a brace integral with the holder and whose free end 75 is turned into substantial alignment with the rim of said cup.

2. A receptacle holder including a platform adapted to support a receptacle, a bracket integral with the platform and upstanding therefrom, spaced hooks carried by 80 said bracket adapted to engage the rim of the receptacle on said platform, a vacuum cup anchored to said holder and adapted to support the same and a pair of legs integral 85 with the bracket on opposite sides of the cup and whose free ends are turned into substantially a common plane with the rim of said cup.

In testimony whereof I have signed my 90 name to this specification.

WILLIAM T. HENRY.
